UNITED STATES PATENT OFFICE.

GEORGE H. BLAXTER, OF BEAVER FALLS, PENNSYLVANIA.

METHOD OF MAKING SEAMLESS TUBES.

1,076,545.

Specification of Letters Patent. Patented Oct. 21, 1913.

Application filed April 8, 1911. Serial No. 619,726.

To all whom it may concern:

Be it known that I, GEORGE H. BLAXTER, a resident of Beaver Falls, in the county of Allegheny and State of Pennsylvania, have 5 invented a new and useful Improvement in Methods of Making Seamless Tubes, of which the following is a specification.

This invention relates to a method of making seamless tubing, and its object is to provide 10 a method of making finished tubing by a rolling process, or in other words making a hot finished seamless tube.

Generally stated the invention consists in first rolling a hot hollow blank over a plug 15 or ball between grooved rolls, and preferably simultaneously therewith forcing it onto a mandrel bar, then rolling the same on a mandrel bar in one or more stands of grooved rolls, and finally reeling or cross 20 rolling said tube, preferably on a mandrel bar.

In the accompanying drawing Figure 1 is a diagrammatic view of the arrangement of apparatus for carrying out the method; 25 Fig. 2 is a detail view illustrating the first step of the operation, or the plug rolling; Fig. 3 is a detail view illustrating the second step of the operation, or the rolling on a mandrel in a grooved mill; and Fig. 4 is 30 a detail view illustrating the third step in the operation, that is reeling or cross rolling the tube on the mandrel.

In carrying out the method I start with a hollow blank 1, which may be either pierced 35 on an ordinary piercing mill, or produced by casting, the former being preferred. This hollow blank is suitably heated before subjecting it to the process steps hereinafter described. In case said blank is produced 40 by piercing a solid billet, the initial heat for piercing will probably suffice. This blank is introduced between the grooved rolls 3 and forced over the plug or ball 4 of mandrel 5, the blank preferably being 45 forced between the rolls by a suitable pusher, such as indicated at 6. The mandrel bar 5 is preferably of such a nature that the tube can be finished thereon, although this is not necessary as the ball or plug may be supported 50 between the rolls 3 by any usual mandrel bar. As shown the bar 5 is of comparatively large diameter, having the terminal ball or plug 4. The rear end of the mandrel bar 5 is supported against a gate 55 or stop 9 which receives the force of the impact during the process of forcing the blank

1 over the ball or plug between the rolls 3, after which operation the ball or plug readily falls away from the mandrel. The effect of this operation, is that the blank is reduced and elongated and cleared of all scale inside and out. If desired the blank may be given a plurality of passes through a plug mill, the mandrel bar for the last pass 60 preferably being adapted to serve as an interior mandrel for the subsequent steps of the process. Preferably, however, only one or two passes in the plug mill are given, while the blank is still quite hot and ductile, so that the liability of interior scores or 65 scratches being produced by the plug is reduced to a minimum.

From the plug mill the partly reduced tube, while supported on the mandrel bar 5, passes to a grooved mill comprising one or 70 more stands of grooved rolls 11, preferably located alternately in horizontal and vertical planes as shown, whereby the tube is subjected successively and alternately to pressures first on top and bottom and then on the 75 two lateral sides. It will be understood that any number of pairs or stands of such rolls may be employed, and that their position with relation to each other may be varied as desired. They need not be arranged alternately with the axes at right angles, but instead the blank may be given a quarter turn 80 between passes. The effect of these grooved rolls is to further compress the walls of the tube upon the mandrel bar, giving it the required uniform thickness throughout and giving it a smooth and substantially polished 85 surface inside and out. Preferably the tube will leave the grooved mill of substantially the desired length and diameter and thickness 90 of wall of the finished tube.

From the grooved mill the tube, while 95 preferably still on the mandrel bar, passes to the cross rolling or reeling mill 13, there preferably being provided between said 100 mills a feed table or trough 14 of slightly greater length than the tube and mandrel bar, so that by the time the forward end of the tube enters the cross rolls it is entirely free from the continuous mill and is therefore 105 free to rotate as it must under the action of the cross rolls. On the exit side of the cross rolls is a similar trough or table 15 to receive the finished tube, from which it can be taken to a stripper of any suitable 110 character. After the tube is stripped from the mandrel bar it may be passed through

sizing rolls if necessary or desired. The action of the reeler or cross rolls is to further smoothen and true the tube interiorly and exteriorly if not already smoothened 5 sufficiently in the grooved mill.

According to the method described it is possible to finish a seamless tube at the initial heat of the billet. When the operation starts with a solid billet it must be 10 heated for piercing, and this heat will be sufficient with the proper handling to enable the tube to be reduced to its final or finished form. All of the operations take place very rapidly, and except when giving a plurality 15 of passes through the plug mill, the blank travels continuously forward with little or no interruption through the entire process. The effect of the plug rolling is to rapidly reduce the blank and clear the same both 20 interiorly and exteriorly of scale, so that it passes onto the mandrel bar with practically clean surfaces so that in the subsequent rolling on the mandrel bar the interior is left perfectly smooth and any scores 25 or scratches which may be therein on account of the rolling in the plug mill, will be removed by rolling the tube against said bar and no further scores or scratches will be produced. The rolling on the mandrel 30 bar in the grooved mills forms a tube which interiorly is practically true, and the subsequent cross rolling or reeling either over the same mandrel bar or over an ordinary drum head mandrel, serves to true the tube 35 and reduce the gage to that finally desired and makes the tube perfectly circular exteriorly and straightens the same. The tube as it comes from the cross rolls is practically in finished form, but if desired may be sized 40 and afterward cold drawn for highly finished product.

With this invention the output of the mill is very large and the cost of production much lower than with the processes 45 usually employed, and the tube produced is so perfect as to dispense entirely with cold drawing, and even for highly finished work where cold drawing is desired, the number of cold drawing passes can be materially 50 reduced on account of the practically smooth and perfect contour both interiorly and exteriorly of the tube.

The several mills illustrated may be of any suitable types, so long as they perform 55 the functions for which they are severally intended.

What I claim is:

1. The method of manufacturing seamless tubing, which consists in rolling a hollow blank in a plug mill to reduce and

elongate the same and free the same from scale, then rolling the same on a traveling bar in a grooved mill to further reduce the same to uniform thickness and smooth the same interiorly and exteriorly, and finally 65 cross rolling or reeling the same to true and further smooth the same.

2. The method of manufacturing seamless tubing, which consists in rolling a hollow blank in a plug mill to reduce and 70 elongate the same and free the same from scale, then rolling the same in a grooved mill on a mandrel bar traveling with the blank through said mill to further reduce the same to uniform wall thickness and produce a smooth interior surface for the tube, and finally cross rolling or reeling the tube 75 while on said mandrel bar to thereby true and further smooth the same without the production of interior scores or ridges. 80

3. The method of manufacturing seamless tubing, which consists in rolling a hollow blank in a plug mill to reduce and elongate the same and free the same from scale and simultaneously pass the same over 85 a mandrel bar, thereby preventing the formation of interior scores or ridges, then rolling the same on said mandrel bar in a grooved mill to further reduce the same to uniform wall thickness and smooth the same 90 interiorly and exteriorly, and finally cross rolling or reeling the same while on said mandrel bar to true and further smooth the same. 95

4. The method of manufacturing seamless tubing, which consists in rolling a hollow blank in a continuous mill and on a mandrel bar traveling with the blank through said mill to reduce and elongate the same to substantially finished gage and 100 length and without the production of interior scores or ridges, and then cross rolling or reeling the same while on said mandrel bar to true and further smooth the same. 105

5. The method of manufacturing seamless tubing, which consists in forcing a heated tubular blank between reducing means over and onto a mandrel bar, and then reducing the tube between said bar and outside reducing means, thereby preventing the formation of interior scores or ridges and finally cross rolling or reeling the tube 110 while on said mandrel bar.

In testimony whereof, I have hereunto set my hand.

GEORGE H. BLAXTER.
